UNITED STATES PATENT OFFICE.

FRED E. ANDERSON, OF OSAGE CITY, KANSAS, ASSIGNOR TO DAVID S. ERICKSON, OF OSAGE CITY, KANSAS.

COMBINED INTAKE MANIFOLD AND FUEL PREHEATER.

Application filed September 27, 1921. Serial No. 503,693.

To all whom it may concern:

Be it known that I, FRED E. ANDERSON, a citizen of the United States, residing at Osage City, in the county of Osage and State of Kansas, have invented certain new and useful Improvements in Combined Intake Manifolds and Fuel Preheaters; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to means for pre-heating the fuel charge to be introduced into the combustion chamber of an internal combustion engine, and one of the objects of the invention is to take advantage of the heat in the cooling water circulated through the cooling jackets about the engine cylinders.

In the physical embodiment of my invention selected for illustration I have shown the invention as adapted to be used with an intake manifold, the mechanical embodiment preferably constituting part of the manifold so that the invention may be applied to existing types of motors by substituting a manifold embodying my invention for the conventional manifold generally used.

The generic principles as well as the specific details of the invention selected for illustration will be apparent by reference to the following description in connection with the accompanying drawings, in which—

Fig. 1 is a side elevational view of an engine to which my invention is applied.

Fig. 2 is a detail perspective view of a manifold embodying my invention and detached from the engine.

Fig. 3 is a sectional view in a plane indicated by the line 3—3 of Fig. 2.

Fig. 4 is a sectional view on the line 4—4 of Fig. 3.

Fig. 5 is a sectional view on the line 5—5 of Fig. 3, and

Fig. 6 is a sectional view on the line 6—6 of Fig. 3.

The manifold may be constructed in the form of a Y, comprising the intake leg 1 and the discharge legs 2 and 3, which are connected by suitable ports to the intake openings of the combustion chambers of the engine. The manifold ports comprising the

openings through the legs 1, 2 and 3 are somewhat modified to merge into a substantially rectangular chamber 4, the bottom of which communicates with the hollow leg 1 and the opposite upper corners of which communicate with the hollow legs 2 and 3. There are baffles 5 in the chamber 4 in staggered relation, as clearly seen in Fig. 6, to thoroughly intermix the constituents of the combustion mixture and to provide heat radiating means whereby the charge can absorb the heat from a heating chamber preparatory to entering the combustion chambers of the engine.

The wall 6 of the chamber 4 encloses one side and the wall 7 the other side. The wall 7 is spaced from another wall 8 to provide a water chamber or space 9 between them and the wall 8 is spaced from an outer wall 10 to provide an air space or chamber 11. The water space 9 is provided with an inlet 12 and an outlet 13 at the top and bottom respectively of the box 14, formed by the walls just described and the top and bottom walls 15 and 16 co-operating with the end walls 17 and 18.

The inlet 12 is connected to the pipe 19 of the water circulating system leading from the radiator 20 through the medium of a branch pipe 21. The discharge port 13 is connected to the radiator 20 through the medium of a pipe 23, as clearly seen in Fig. 1, so that water may circulate from the system through the chamber 9 and back to the system, supplying heated water at the temperature at which the water passes through the cooling jackets.

At right angles to the ports 12 and 13 are air inlet and exhaust ports 24 and 25 respectively. The inlet 24 is open to atmosphere and the outlet 25 is connected to a carburetor 26 through the medium of a conduit or pipe 27. The carburetor 26 is connected to the intake end 28 of the leg 1 of the manifold. The chamber 9 is provided with baffles or heat radiating fins 29, as clearly seen in Fig. 5, these being preferably in staggered relation, and similar fins 30 are arranged in the chamber or space 11 to absorb the heat by induction from the water passing through the chamber 9.

When the parts are assembled with the chamber 9 connected to the water circulating system of the engine, water will pass through the chamber 9 in a continuous stream, in-

duced by the circulating pump or otherwise, as will be clearly apparent. Atmospheric air will enter the port 24, passing through the chamber 11 where it will come into contact 5 with the wall 8 and the fins or baffles 30, absorbing heat and then passing through the conduit 27 to the carburetor 26, where the heated air will absorb the hydrocarbon from the carburetor in an efficient manner and 10 from the carburetor pass into the leg 1 of the manifold, at this time being impregnated with the hydrocarbon content of the fuel mixture. As the fuel mixture passes through the leg 1 into the legs 2 and 3, it must 15 traverse the chamber or space between the walls 6 and 7, where it will absorb additional heat from the fins 5 and the wall 7 constituting part of the enclosure for the space 9, through which the hot water passes. 20 The combination at a relatively high temperature will then pass through the hollow legs 2 and 3 into the combustion chambers of the engine cylinders, efficiently preheated, with the known advantages of preheated 25 fuel charges supplied to internal combustion engines.

It will be apparent that the device will efficiently perform the functions for which it is intended and that the combined manifold and temperature raising means may be 30 constructed with the manifold legs of such proportions that the manifold may be readily substituted for the conventional types

of manifolds without re-arranging any of the parts of the engine other than to tap in for the supply water to be circulated through the chamber or space 9. 35

The device can be constructed as a single casting or the walls 8 and 10 may be formed separately and welded to the manifold. If 40 welded, the device will be made into an integral unitary structure, it being also apparent that the parts may be separately deformed in other ways and assembled if desired. 45

What I claim and desire to secure by Letters Patent is:

An intake manifold for internal combustion engines comprising a casing divided into an intermediate heat chamber and two outer chambers, one of which is a fuel chamber and the other an air chamber, an inlet port for the fuel chamber, and exhaust ports for said chamber, the intermediate chamber having ports at its top and bottom and the air chamber having ports at its respective ends at right angles to the ports in the heat chamber, one air port communicating with atmosphere and the other having means for attachment to a carburetor, the inlet port for the fuel chamber having means for attachment to the discharge end of the carburetor. 50 55 60

In testimony whereof I affix my signature.

FRED E. ANDERSON.
